CLAIM

The ornamental design for cover for shoe-making machine, as shown.

DESCRIPTION

FIG. 1 is a perspective view, from the right-hand side, of the cover for shoe-making machine in accordance with my new design;

FIG. 2 is a right-hand side elevation of the cover shown in FIG. 1;

FIG. 3 is a left-hand side elevation of said cover; and,
FIG. 4 is a top plan view of said cover.

FIG.1

FIG. 2

FIG. 3

FIG. 4
